UNITED STATES PATENT OFFICE.

GEORGE H. ROGERS, OF BIRMINGHAM, ALABAMA.

PAPER-FILE.

SPECIFICATION forming part of Letters Patent No. 624,544, dated May 9, 1899.

Application filed March 19, 1898. Serial No. 674,443. (No model.)

To all whom it may concern:

Be it known that I, GEORGE H. ROGERS, a citizen of the United States, and a resident of Birmingham, Jefferson county, and State of Alabama, have invented a certain new and useful Paper-File; and I do hereby declare the following to be a full, clear, and exact description of the invention, such as will enable others skilled in the art to which it appertains to make and use the same, attention being called to the accompanying drawings, with the reference-numerals marked thereon, which form a part of this specification.

This invention relates to a device for filing papers like periodicals and newspapers to confine and hold them together in regular order and for convenient use.

The object of my invention is to provide such a device, commonly known as a "paper-file," which permits convenient and ready attachment or removal of the papers and at the same time is of a simple and inexpensive but durable construction.

In the following specification, and particularly pointed out in the claim, is found a full description of the invention, its manner of use, parts, and construction, which latter is also illustrated in the accompanying drawings, in which—

Figure 1 shows the device in one of the positions it appears in when used with papers attached in front of a reader. Fig. 2 shows the same device in a position when not in use—as, for instance, when hung up. Fig. 3 shows it without any papers, but with parts adjusted to permit placing of such. Fig. 4 is an enlarged cross-section on line 4-4 of Fig. 2.

The device consists, primarily, of a narrow rectangular frame, preferably of metal. On one of the long members (numbered 7 in this instance) are two pins 8, one near each end. They project toward the other member, (num-

bered 9,) but terminate so as to leave a space between their pointed ends and said member. A paper 10 to be attached is passed in edge-wise through this space, as may be readily understood, until its folding-line is above the points of the pins, when the paper is forced down over them and toward member 7. The papers are held in position against the latter, as most plainly shown in Fig. 2, by a strip of resilient material connected midway between its ends at 11, and its free ends forming springs 12, one to either side of its point of connection. These free ends are shaped as shown and have a normal tendency toward member 7, close approach to which is permitted by holes 13 in said springs, which thus clear the pins. When a paper is to be inserted, these springs are retracted toward member 9, as shown in Fig. 3, to clear pins 8 and held so by sliding loops 14 until the paper is placed. After that these loops are shifted again toward the center, as shown in Fig. 2, whereupon the free ends of the springs assume their normal position and by pressing the paper against member 7 hold the same on the pins and in place.

Fig. 2 shows a convenient manner of supporting the file on hooks 15, which are shaped as shown in Fig. 4.

Having described my invention, I claim as new—

A paper-file consisting of two long members 7 and 9 arranged parallel and connected to each other at their ends, pins 8 on one member and springs 12 and loops 14 on the other all as shown and described.

In testimony whereof I hereunto affix my signature in presence of two witnesses.

GEORGE H. ROGERS.
